TURNTABLE

Hugh B. Hall, Opelika, Ala.

Application August 24, 1946, Serial No. 692,777

1 Claim. (Cl. 248—131)

1

This invention relates to new and useful improvements and structural refinements in turn tables, and the principal object of the invention is to provide a device of the character herein described, which is particularly adapted for use by persons engaged in the packing of boxes, more specifically, in the packing of flowers in boxes, and similar containers.

A further object of the invention is to provide a turn table which will save the workman a considerable amount of time by eliminating unnecessary lost motion during the packing operation. It should be understood that flowers are usually packed in boxes by being arranged in one end of the box and then in the other, whereupon it is necessary to lift the box and turn over the same, in order that the tying cord may be passed, both longitudinally and transversely, around the packed box. It will thus be clearly apparent that in order to perform this packing operation in accordance with conventional practice, the worker first stands on one side and at one end of the box, and hence walks to the opposite side and end, before the packing operation is completed. The movement from one side of the box to the other is usually necessary to maintain the right-handed (or left-handed) position or relationship of the worker with respect to the box. After the packing operation has been completed, the worker must then lift the box several times in order to pass the tying cord around the same, as has already been set forth.

Another object of the invention is to provide a turn table which is simple in construction and the use of which will totally eliminate the previously necessary movement of the worker around the box and the lifting of the same, as aforesaid.

An additional object of the invention is to provide a turn table which is pleasing in appearance and which will not easily become damaged.

A still further object of the invention is to provide a turn table which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is an end view of the invention.

Figure 2 is a side elevation thereof.

Figure 3 is a perspective view of the same.

Figure 4 is a top plan view of a modified embodiment of a base used in the invention, and

2

Figure 5 is a side elevation of the subject shown in Figure 4.

Like characters of reference are used to designate like parts in the specification and throughout the several views.

Referring now to the accompanying drawings in detail, the invention consists of a turn table designated generally by the reference character 6, the same embodying in its construction a substantially cubical body 7 constituting what may be referred to as a base, designated by the same reference numeral.

The base 7 may be formed from any suitable material such as concrete, cast-iron, or the like, whereby the same possesses sufficient weight and stability to support the structure hereinafter more fully described.

An upright tube 8 is embedded in the base 7 and projects upwardly therefrom and a shaft 9 is rotatably positioned in the tube 8, as will be clearly apparent from the accompanying drawings.

A horizontally disposed cross bar 10 is secured by welding, or in any other suitable manner, to the upper end of the shaft 9, the bar 10 extending in relatively opposite directions from the shaft, as is best shown in Figures 2 and 3.

An inverted, substantially triangular end-piece 11 is secured at the apex 12 thereof to each end of the cross bar 10, each of the end-pieces 11 consisting of a length of rod angulated substantially as shown to produce the required configuration. A further rod forming a diagonally extending strut 13 extends between the geometric base, that is, the upper, horizontally disposed portion 14 of each of the pieces 11 and the cross bar 10, as will be clearly apparent from the accompanying drawings. The purpose of the struts 13 is, of course, to securely retain the end-pieces 11 in a rigid relationship with respect to one another and to the cross bar 10.

When the invention is placed in use, the packing box (not shown) is positioned on the portions 14 of the end-pieces 11 and it will be observed that the packing operation may be undertaken with the workman standing in one position, while the carrier consisting of the end-pieces 11 together with the cross bar 10 and the shaft 9, is rotated in the tubular socket 8.

When the packing operation has been completed, the tying cord may be conveniently passed around the box, transversely, by virtue of the spacing provided by the end-pieces 11, while the longitudinal tying of the box may be undertaken by simply lifting the box at one end and then at

55

the other, while the cord is being passed thereunder.

Referring now to the accompanying Figures 4 and 5 which illustrate a modified embodiment of the base, such as may be effectively employed in substituting for the aforementioned base 7, the modified base designated generally by the reference character 15 consists of an integral casting comprising a substantially frusto-conical body portion 16 provided at its minor end with a shoulder 17 and standing on a substantially square base or platform 18.

The body portion 16 is cored in a suitable manner as at 19, and forms a vertically disposed cylinder 20 provided with an axially extending bore 21.

This bore is, of course, adapted to rotatably receive the aforementioned shaft 9 and it will be noted that the base 18 is also provided with a plurality of apertures 22 in which suitable screws may be positioned for mounting the base upon its supporting structure.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor 30

changes in the details of construction, combination and arrangement of parts may be resorted to without departing from the spirit and scope of the invention as claimed.

5 What I claim as my invention is:

A turntable comprising in combination, a body forming a base, an upright tube secured in and projecting upwardly from said base, a shaft rotatably positioned in said tube, a cross bar secured medially of its length to the upper end of said shaft, lengths of rod angulated to form inverted, substantially triangular end-pieces, each of said end-pieces being secured at the apex thereof to one end of said cross bar, the upper portion of said rods being horizontally disposed and constituting carrier arms, and diagonally extending struts between each of said arms and said cross bar.

HUGH B. HALL.
